UNITED STATES PATENT OFFICE

CHARLES F. KETTERING, OF DAYTON, OHIO, ASSIGNOR TO FRIGIDAIRE CORPORATION,
OF DAYTON, OHIO, A CORPORATION OF DELAWARE

REFRIGERATING APPARATUS

Application filed December 31, 1928. Serial No. 329,428.

This invention relates to refrigerating apparatus of the absorption type.

One of the objects of the invention is to provide absorption refrigerating apparatus which may be readily and effectively cooled by air.

Another object is to provide an apparatus using solid absorbent and which produces substantially continuous refrigeration.

10 Still another object of the invention is to provide an improved and simplified arrangement of the component parts of the apparatus.

Further objects and advantages of the present invention will be apparent from the following description, reference being had to the accompanying drawings, wherein a preferred form of the present invention is clearly shown.

20 In the drawings:

Fig. 1 is a diagrammatic illustration of a refrigerating system embodying the invention, certain parts being shown in section;

Fig. 2 is a plan of a portion of the apparatus shown in Fig. 1;

Fig. 3 is a section on the line 3—3 of Fig. 1;

Fig. 4 is an enlarged section of a control valve;

Fig. 5 is an enlarged section of a thermostat corresponding to Fig. 3; and

Fig. 6 is a section of the thermostat on the line 6—6 of Fig. 5.

The refrigerating system shown in the drawings includes two generator-absorbers 10 and 11 each of which is charged with a suitable absorbent, preferably a solid such as calcium chloride or activated charcoal. Each intermittently supplies liquid refrigerant, for example ammonia, to an evaporator 12 and intermittently withdraws gaseous refrigerant from the evaporator. The generator-absorber 10 is connected to one end of the evaporator by means of the circuit including the conduit 10a, condenser 10b and control valve 10c, while the generator-absorber 11 is similarly connected to the other end of the evaporator through the conduit 11a, condenser 11b and control valve 11c. When either generator-absorber is heated and the other 59 generator-absorber is simultaneously cooled,

liquid refrigerant is supplied to the evaporator by the heated generator-absorber and its condenser and gaseous refrigerant is withdrawn from the evaporator by the cooled generator-absorber. This eventually exhausts the heated generator-absorber of its refrigerant and saturates the cooled generator-absorber with refrigerant. When one generator-absorber has thus been exhausted, the heating and cooling are reversed so that the saturated generator-absorber is now heated to distill refrigerant and the exhausted one cooled to absorb the refrigerant.

Each generator-absorber may be formed in any suitable manner, for example by a pair 65 of co-axial tubes 14 and 15, the space between which is closed by plates 16 to form a substantially annular chamber 17 in which the absorbent is placed. The inner tube 15 forms a flue both for heating and cooling 70 the generator-absorber and for this purpose is provided on its interior surface with fins 18 to increase the rate of heat flow into or out of the generator-absorber. The outer tube 14 is provided with an inlet and outlet 75 passage 19 for the chamber 17, connected to the conduit 10a or 11a.

The means for heating either generator-absorber is a burner 22 which may be placed at the lower extremity of the flue provided 80 by the tube 15. The means for cooling either generator-absorber is a flue with which is associated a fan or blower 24 and which may be placed to direct a current of air through the flue 15. As illustrated, the blower is of 85 the centrifugal type having its intake at the connection 27, but the particular form of air moving device is immaterial to the invention. The flue includes a stationary portion 25 and a movable portion 26 in the general form of 90 a goose-neck which may be rotated about the connection 27 so that its intake end 28 may register with the flue in either generator-absorber 10 or 11. The burner is preferably surrounded by and supported in a shield 32 95 adapted to form an extension of the flue 15. The shield and intake end 28 of the flue are connected to and supported by a plate 34 which is keyed to a shaft 35 journaled in stationary bearings 36 which are in alignment 100

with the axis of the connection 27. The shaft 35 may be rotated to bring the intake end 28 of the flue in register with either generator-absorber 10 or 11 and simultaneously 5 to bring the burner shield 32 in register with the other generator-absorber 11 or 10. Fuel is continuously supplied to the burner 22 through a rotatable connection 38 to a stationary pipe 39 supported in the connection 10 27. The blower is driven continuously by any suitable mechanism such as a motor 40 and continuously produces a draft through the stationary portion 25, connection 27 and the movable portion 26 of the flue. Preferably both condensers 10b and 11b are mounted in or adjacent to the stationary portion 25 of the flue so as to be always cooled by the draft. The arrangement is such that one generator-absorber and the condenser associated with the other generator-absorber are cooled simultaneously but the air reaches the absorber before passing over the condenser. The reason for this is that a lower temperature may be required in the absorber than in 25 the condenser.

With the parts in the position shown in Fig. 1 refrigerant is being driven off from generator 11 and condensed in the condenser 11b by the draft through the flue, from which 30 it flows in liquid form through the control valve 11c to the evaporator.

As shown in Fig. 4 the control valve includes a float chamber 44 having a liquid inlet connection 45 and a liquid outlet connection 46, the latter controlled by a valve 47 actuated by a float 48. The float normally closes the valve and prevents communication between the condenser and the evaporator. However, when sufficient liquid refrigerant accumulates in the float chamber 40 the float is raised to open the valve and permit a quantity of liquid to flow into the evaporator. In order that gaseous refrigerant may be drawn from the evaporator by either 45 absorber the float valves 10c and 11c are each by-passed by a connection 50 having a check valve 51 which permits gas to flow from the evaporator to the absorber but prevents the flow of refrigerant in the reverse 50 direction.

Any suitable means may be used for automatically effecting the intermittent heating and cooling of each generator-absorber in response to the condition of the system. In 55 Figs. 1, 2 and 3 I have shown one form of such means. A drum 60 is attached by a ratchet connection to the upper end of the shaft 35 and a cord 61 is wound upon the drum, passed over a pulley 62 and connected 60 to a weight 63. This weight constantly tends to rotate the shaft counter-clockwise as seen in Fig. 2. Rotation of the shaft is permitted or prevented in accordance with the condition of the refrigerating system by means 65 of a pair of thermostats 100 and 110 asso-

ciated with the generator-absorbers 10 and 11 respectively. As shown in Fig. 3 each thermostat includes a casing 70 thermally associated with the generator-absorber shell and containing a stack of bimetallic plates 72. 70 A rod 73 having a head 74 urged down by a spring 75 passes through the plates and tends to project from the bottom of the casing in the path of the plate 34 when the thermostat is cold. However, when the thermostat is warm the rod is raised out of the path of plate 34 to permit rotation of the plate. The two rods 73 are placed diametrically opposite to each other with the shaft 35 as a center and the plate 34 is provided with a hole 34a which may register with either rod. 75

Assuming that the thermostat 100 is warm and that that thermostat 110 is cold, the thermostat 100 will withdraw its rod from the path of the plate and the plate will rotate until the rod of the thermostat 110 is projected by its spring 75 through the hole 34a. This will lock the plate in the position shown in Fig. 1 so that the generator-absorber 11 90 will be heated and the generator-absorber 10 will be cooled. As soon as the generator-absorber 10 is cooled to a predetermined degree its thermostat rod 73 will be urged downwardly against the plate by its spring 95 75. As soon as the thermostat 110 has been heated to a predetermined degree the rod will be removed from the hole 34a and the plate will rotate under the influence of the weight 63 until hole 34a comes opposite the 100 rod of the thermostat 100, when the rod will be projected through the opening 34a and lock the plate in such position that the burner 22 is under the generator-absorber 10 and the flue 28 is under the generator-absorber 11. 105

Thus the thermostats automatically switch the heating and cooling from one generator-absorber to the other as is required by the condition of the system.

While the form of embodiment of the invention as herein disclosed, constitutes a preferred form, it is to be understood that other forms might be adopted without departing from the spirit of the invention. For example, instead of a single refrigerant circuit, 115 as shown in Fig. 1, I may use a pair of separate refrigerant circuits each having its own evaporator, the evaporators being refrigerated intermittently to cool continuously a 120 given space.

What is claimed is as follows:

1. Refrigerating apparatus comprising in combination a pair of generator-absorbers to be operated alternately, a flue for circulating 125 air, said flue having a movable portion, a heater carried by said portion and spaced therefrom, and means for moving said portion to bring the heater in heat exchange relation with either generator-absorber and to 130

circulate air in heat exchange relation with the other generator-absorber.

2. Refrigerating apparatus comprising in combination a pair of generator-absorbers to be operated alternately, a rotatable member adapted in one position to heat one generator-absorber and to cool the other generator-absorber, means tending constantly to rotate the member, and means responsive to the condition of each generator-absorber for retaining the member in one position and for permitting the member to be rotated to its other position upon the occurrence of a predetermined change in the condition of the same generator-absorber.

In testimony whereof I hereto affix my signature.

CHARLES F. KETTERING.
